(57) **CLAIM**

I claim the ornamental design for an amputated limb cover, as shown and described.

DESCRIPTION

FIG. 1 is a front view of the amputated limb cover.

FIG. 2 is a top view of the claimed design.

FIG. 3 is a bottom view of the claimed design; and,

FIG. 4 is a perspective view of the claimed design.

The broken lines depict portions of a limb cover and form no part of the claim.

1 Claim, 4 Drawing Sheets**FIG. 1**

FIG. 2

FIG. 3

FIG. 4
